C. F. MILLER,
MULTIPLE FEED HORIZONTAL UNDERFEED STOKER,
APPLICATION FILED SEPT. 19, 1916.

Patented Sept. 14, 1920.

UNITED STATES PATENT OFFICE.

CHARLES F. MILLER, OF PITTSBURGH, PENNSYLVANIA, ASSIGNOR TO WESTINGHOUSE ELECTRIC & MANUFACTURING COMPANY, A CORPORATION OF PENNSYLVANIA.

MULTIPLE-FEED HORIZONTAL UNDERFEED STOKER.

1,352,465.

Specification of Letters Patent. Patented Sept. 14, 1920.

Application filed September 19, 1916. Serial No. 120,978.

To all whom it may concern:

Be it known that I, CHARLES F. MILLER, a citizen of the United States, and a resident of Pittsburgh, in the county of Allegheny and State of Pennsylvania, have made a new and useful Invention in Multiple-Feed Horizontal Underfeed Stokers, of which the following is a specification.

This invention relates to underfeed stokers and particularly to stokers of that type ordinarily termed horizontal underfeeds and which are provided with horizontal retorts.

An object of the invention is to produce a horizontal type of stoker, in which means are employed for eliminating the difficulties ordinarily encountered in such stokers by reason of clinkers adhering to the side walls of the furnace.

A further object is to produce a horizontal underfeed stoker in which means are employed for so feeding fuel to the furnace that the side walls of the furnace are protected from the heat of combustion by the fuel entering the furnace.

25 A further object is to produce an underfeed stoker in which new and improved means are employed for delivering forced draft to the furnace.

30 A further object is to produce a horizontal underfeed stoker in which improved means are employed for preventing coal or finely divided fuel from dropping from the fuel supporting surfaces into the blast delivery ducts or passages.

35 A further object is to produce a new and improved grate bar or fuel supporting element for furnaces in which means are employed for adequately cooling the bar and for, at the same time, preheating the air or blast delivered to the fuel bed of the furnaces.

40 A further object is to produce a new and improved horizontal underfeed stoker, which is of simple construction, is light, has a high fuel burning capacity and is simpler to operate than stokers of that type now in use and known to me.

45 These and other objects, which will be made apparent throughout the further description of the invention, are attained by means of a stoker embodying the features, and to some extent the details of construction, herein described and illustrated.

In the drawings accompanying and forming a part hereof, Figure 1 is a transverse, 55 vertical, sectional view of a stoker embodying my invention. Fig. 2 is a perspective view of a combined pedestal and spacer member which forms a detail of my invention. Fig. 3 is a fragmental perspective 60 view, illustrating the means employed for mounting the moving and stationary grate bars, which form a part of the stoker illustrated. Fig. 3 is so located, with relation to Fig. 2 of the drawings, that it illustrates 65 the method of mounting the grate bar supporting and actuating elements on the combined pedestal and spacer member.

The stoker illustrated, as an embodiment of my present invention, includes two fuel feeding retorts 4, each of which is located immediately adjacent to one side wall of the furnace and is adapted to feed fuel onto and over an adjacent set of moving and stationary grate bars 5. The grate bars as 70 shown extend at right angles to the longitudinal axis of the retort and, as shown, may be inclined downwardly so that the fuel issuing from the retort is fed over them and is finally discharged on to dump grates 75 6, which are located between the two sets of grate bars and are adapted to discharge ash and clinker into an ash pit, located below the central portion of the furnace.

As illustrated each retort 4 is substantially horizontal, extends from the front to the rear of the furnace, and is adapted to receive fuel from a hopper or other receptacle located on the outside and preferably at the front of the furnace. Any suitable 90 means, such as one or more reciprocating plungers, may be employed for feeding fuel into and through each retort and for forcing the fuel upwardly out of the retort and onto adjacent grate bars. Each retort is mounted on pedestals 7, which are suitably spaced along the side walls of the furnace and are so constructed as to form a frame which supports side walls 8 and 9 and a base plate 10, which constitute the retort. This is accomplished by making each pedestal 7 more or less U shaped so that it is provided with upwardly projecting wall supporting arms 11 and 12. The arm 11 is adapted to support the wall 8 in a vertical position and is 100 so arranged that an air passage is provided 105

between the wall 8 of the retort, and the adjacent side wall of the furnace. The retort wall 9 is preferably inclined so that the mouth of the retort is wider than the base. For this reason the wall supporting surface of the arm 12 is inclined. The lower edge of each side wall 8 and 9 is adapted to engage a separate rib 13, formed on the pedestal 7, whereas the side walls are bolted 10 or otherwise rigidly secured to the arms of the pedestals. The base plate 10 is shown mounted on the rib engaging flanges of the side walls 8 and 9 and may be secured in place in any suitable manner.

15 To each pedestal 7 is secured by bolts or otherwise a spacing member 14 which forms a support for the grate bars 5, of one set, and for partition plates 15. The plates 15 divide the space, under each retort and its 20 coöperating set of grate bars, into two compartments or chambers 16 and 17, the former of which may be termed the primary air chamber, whereas the latter may be termed the secondary air chamber.

25 As illustrated each spacer member 14 consists of a base 18, two up-rights 19 and 20, and a web or truss member between the up-rights. The truss member consists essentially of two inclined cords 21 and 22, 30 both of which terminate at the lower ends in a horizontal cord 23. These top cords of the truss member form the supporting surfaces for the partition plates 15. The up-right 19 forms a support for a separately 35 formed grate-bar-supporting air box 24 and the up-right 20 terminates in a lug 25, which forms a support for a member 26 and operates with the upper end of the adjacent arm 12, of the pedestal 7, in forming a bearing 40 for a rock shaft 27.

The partition plates 15 mounted on the inclined cord members 21, of the spacers 14, are adapted to be notched out so that the lug 25 and the upper end of the arm 12 project through them, or so that the upper edges of the plates abut against the upper edge of the side wall 9 of the retort. For this purpose I have provided the arm 12, of each pedestal, with a downwardly inclined laterally projecting flange 28, which in effect forms an extension of the cord member 21 and is adapted to secure one notched edge of a plate 15 in place. The cord member 21 is extended on the other 50 side of the lug 25 or the lug 25 is provided with a laterally projecting inclined flange which forms a corresponding support for the other notched edge of a plate 15. The partition plates supported on the cord member 22 of the spacers 14 engage the air box 24 and consequently communication between the air chambers 16 and 17 is absolutely cut off, except through the air box 24 and the grate bars, as will be described.

55 The grate bars 5 of each set are mounted

on one member 26 and one of the air boxes 24. The member 26 is provided with a laterally projecting flange which rests upon the upper edges of the lugs 25 of the spacers 14 and the member itself is bolted, or otherwise rigidly secured to the lateral faces of the lugs. In this way it not only forms a support for the grate bars but acts as a tie member between the members 14. The air box 24, as illustrated, is channel shaped and 70 its flanges project downwardly on opposite sides of the upper ends of the up-rights 19, of the spacers 14, and are adapted to be rigidly secured to them. With this arrangement the air box is in open communication 75 with the chamber 16. It is provided in its upper or grate-bar-supporting face with a series of regularly spaced air delivery ports 80 31, which are adapted to deliver air or blast from the chamber 16 into air passages 85 formed within the grate bars 5.

As illustrated each grate bar is provided with a substantially U shaped air passage 32 which is adapted to communicate at one end with a port 31, of the air box, through 90 a port 33 formed in the air-box-engaging face of the bar, and which extends along the inner surface of the top of the bar to the inner or retort end of the bar and then back along the lower wall of the bar and 95 terminates in a delivery port 34, located adjacent to the air box engaging end of the bar and communicating with one of the secondary air chambers 17. In this way air entering each grate bar passes first along 100 the upper or fuel supporting wall of the bar and then is reversed and passes back along the lower wall of the bar and is finally discharged into a secondary air chamber, from which it is delivered to the fuel bed 105 through air delivery openings between the grate bars 5. Each grate bar 5 is also provided with twyer openings 35, located at the retort end of the grate bar and communicating with the passage 32. These openings 110 discharge air from the passage 32 into the mass of green fuel as it issues from the retort, and they are preferably so located in the bars that the blast issuing from them passes across the mouth of the retort. 115

Blast is also discharged into the fuel issuing from the retort through twyer openings 36 located on the opposite side of the retort. As illustrated the openings 36 are formed in the retort wall 8 near its upper 120 edge and extend throughout the length of the retort. These openings communicate with the space between side wall 8 and side wall of the furnace and are consequently in open communication with the chamber 16. 125 Inasmuch as the blast entering the fuel bed through these ports is not preheated, it to some extent keeps down the temperature of the fuel bed immediately adjacent to the side wall of the furnace and thereby in- 130

creases its protective effect of the fuel on the side wall.

In the stoker illustrated alternate bars 5 of each set are stationary whereas the intermediate bars are reciprocated longitudinally by means of the rock shaft 27 which may be oscillated by any suitable means, such as a stoker engine located at the front of the furnace. The moving grate bars are 10 operatively connected to the rocker arm by prongs 27^a and not only aid the fuel in its progress from the retort to the dump grates 6 but also agitate the breaking up of the fuel bed and tend to prevent the formation 15 of large clinkers. It will of course be understood that the grate bar supporting surface of the air box 24 is proportioned to accommodate the reciprocation of the moving grate bars and that the ports 31 and 33 20 formed in the air box and in the grate bars respectively are so proportioned that they will not cut down the flow of air through them at any time during the reciprocation of the moving grate bars. The stationary 25 grate bars are operatively connected to the support members 26 by prongs 26^a.

The dump grates 6, as illustrated, are pivotally mounted on lugs 38 formed on the air boxes 24. The free ends of the grate 30 bars 6 are adjacent to each other and the grates are adapted to swing downwardly for the purpose of dumping the ash and refuse material into the ash pit.

The operation of the stoker illustrated, is 35 as follows: Fuel is continuously or periodically fed into each retort 4 at a point below the surface of the fuel maintained within the retort or on the fuel supporting surfaces of the furnace. Fuel entering each retort 40 crowds fuel within the retort upwardly and onto the adjacent grate bars 5. The continual or periodical upheaval of fuel within each retort occasions a crowding action within the fuel bed and causes the fuel 45 bed to distribute itself over the grate bars 5 and dump grates 6. As already described this distributing action is aided by the reciprocation of the moving grate bars, and to some extent by the inclination of the 50 bars. The blast delivered to the fuel bed is received first by the primary air chamber 16. As illustrated each chamber 16 receives blast from an air duct or passage 39, which is located within the foundation of the 55 furnace, and the delivery of blast from each duct may be controlled by a valve 39^a. Air from each chamber 16 is delivered through the twyer openings 36 and also through the ports 31 of the cooperating air box 33. The 60 air passing through the ports 31 is, as previously described, delivered to the air passages of the grate bars and in passing through the grate bars not only cools them but is itself heated. A portion of the air 65 traversing the passages 32 of the grate bars

is delivered through the twyer openings 35 formed in the grate bars whereas the remaining portion is delivered through ports 34 to the secondary air chamber 17. The grate bars are so formed that air delivery 70 passages are provided between them. This is accomplished by providing a spacing projection 40 on each side of each end of each grate bar, the projections coöperating to space the grate bars and to provide the 75 necessary air passages between them.

In Fig. 1 I have illustrated a damper controlled port 43 for delivering air under pressure to the ash pit or below the dump 80 grates 6. This port is shown in communication with one of the primary air chambers 16 and the damper 44 which controls it may be actuated from the front of the stoker if desired. With this arrangement blast to the ash pit may be shut off without 85 shutting off the blast to the other parts of the furnace or it may be controlled in such a way that there will be no tendency for the blast to blow holes through the portion of the fuel bed supported on the dump grates. 90

The dump grates may be actuated from the front of the furnace by any suitable means, and the portion of the furnace above the dump grates is preferably accessible through doors located in the front, and if 95 desired in the rear of the furnace. It will be apparent that coal sifting will have no detrimental effect on the operation of the stoker since it cannot enter the primary air chambers nor is there any possibility for 100 such sifting to interfere with the operation of the stoker. The fine coal or ash, dropping through the openings between grate bar 5, and the fine coal, dropping through the openings between the retort ends of the 105 grate bars and the upper edges of the retorts, fall into the secondary air chambers 17. The inclined walls of these air chambers cause the siftings to collect on the horizontal floor of the chambers from which 110 it may be removed through the doors formed in the front or rear of the furnace as desired. With this arrangement the sifted coal can be readily and quickly removed by merely shutting down the blast 115 while the doors in the front of the furnace are open.

One of the advantages of the furnace illustrated is that clinkers may be readily removed from the fuel bed and consequently 120 the operation of cleaning the furnace is materially simplified. There is no possibility of the clinkers adhering to the parts of the furnace, since the reciprocations of the moving grate bars will break the clinkers free 125 from the ends of the grate bars and will also prevent them from adhering to the exposed surfaces of the air box. In cleaning the stoker the clinkers will preferably be broken up by a punch bar, inserted from 130

the front or possibly from the rear of the stoker and after they are freed from the portions of the fuel bed supported by the grate bars the dump grates 6 may be dropped thereby discharging all of the clinkers and ash into the ash pit. If the clinkers are properly broken up so as to prevent arching across the dump grates, the cleaning of the furnace will be very simple and will not occasion a loss of fuel, since the portion of the fuel bed supported on the grates 5 will be freed from the clinkers and ash prior to the dumping operation and there will be no tendency for it to avalanche into the ash pit.

Another important feature of my invention is the means employed for introducing the blast or the air into the fuel bed. This is accomplished by the form and the arrangement of the grate bars and is a material improvement over the blast delivery means of horizontal stokers now in use and known to me. Another feature of the invention is that the operating mechanism of the moving grate bars is cooled by the air or blast entering the furnace. This is accomplished by locating it in the secondary air chambers.

Other features of my invention are, that the retorts 4 may be removed from the furnace without in any way affecting the adjustment of the grate bars 5 or of their operating mechanism, and that there is no opportunity for fuel to enter the primary air chambers.

While I have illustrated and described but one embodiment of my invention it will be apparent that various changes, substitutions, modifications, additions, and omissions may be made in the apparatus illustrated without departing from the spirit and scope of the invention as set forth in the appended claims.

What I claim is:

1. In an underfeed stoker, grate bars, a horizontal retort, pedestals on which the retort is detachably mounted, a rocking bar supported by the pedestals for reciprocating some of said grate bars, and means supported by the pedestals for supporting the grate bars independently of the rocking bar and the retort to permit removal of the retort without disturbing the grate bars.

2. In an underfeed stoker, a horizontal retort to and through which fuel is fed, a set of grate bars located on one side of the retort, each grate bar of the set extending into proximity with an upper edge of the retort, a separately formed pedestal on which the retort is detachably mounted, a spacing member secured to said pedestal and on which the grate bars are mounted independently of the retort, and partition plates mounted on the pedestal and spacing member and dividing the space below the

retort and the grate bars into two air chambers, one of which receives air from the other.

3. In an underfeed stoker, a fuel-feeding retort having twyer openings adapted to discharge across the mouth thereof, a dump grate, grate bars receiving fuel from the retort and delivering onto the dump grate, means for dividing the space below the grate bars and retort into two compartments and the space below the dump grate into a separate compartment, said grate bars having air passages affording communication between the compartments therebeneath, and means for delivering air from one of the first two compartments to said retort twyer openings and to the compartment under the dump grate.

4. In an underfeed stoker, a fuel-feeding retort having twyer openings in a side thereof, a dump grate, grate bars adapted to receive fuel from the retort and to deliver onto the dump grate, means for segregating the space immediately below the grate bars from the rest of the space below the fuel supporting elements of the stoker, said grate bars having longitudinal air passages communicating with said segregated space and having twyer openings at the retort ends adapted to discharge air from said passages across the mouth of the retort, means for segregating the space below the dump grate, and means for separately delivering air to the grate bar passages, to the retort twyer openings, and to the segregated space below the dump grate.

5. In an underfeed stoker, a fuel feeding retort having twyer openings, a dump grate, grate bars receiving fuel from the retort and delivering onto the dump grate, means for dividing the space immediately below the fuel supporting elements into two compartments, said grate bars being provided with passages adapted to afford communication between said compartments and with twyer openings at the retort ends thereof communicating with said passages, means to supply air under pressure to one of said compartments, and means for supplying air from the last referred to compartment to said retort twyer openings.

6. A horizontal underfeed stoker comprising two substantially horizontal fuel feeding retorts, each retort having twyer openings, a dump grate mechanism located substantially midway between the retorts, two sets of grate bars, each located between a retort and the dump grate and provided with air passages, and means for dividing the space below the stoker into separate air compartments, a compartment being located immediately under each set of bars and receiving air passing through the passages in the bars, another compartment beneath each of said compartments communicating with

the said passages in the bars and twyers in the retort, and another compartment under the dump grate communicating with one of the last named compartments.

5 7. A horizontal underfeed stoker, comprising two substantially horizontal fuel feeding retorts, each located immediately adjacent to a side wall of the furnace, a dump grate mechanism located in substantially the center of the furnace at a point midway between the retorts, a separate set of grate bars located between each retort and the dump grate mechanism, each set being inclined downwardly toward the dump 15 grate mechanism, and comprising moving and stationary grate bars, means for isolating the space immediately below each set of grate bars, each set of grate bars having passages in communication with the space therebeneath, means for supplying air under pressure to said grate bar passages, and means for excluding air from the space below the dump grate.

8. An underfeed stoker, comprising at 25 least two horizontal retorts extending from the front to the rear of the stoker, a dump grate located between the retorts, a separate set of grate bars between each retort and the dump grate, pedestals on which each 30 retort is mounted, supporting and spacing members secured to the pedestals on which the grate bars of each set are mounted, partition plates mounted on the grate-bar-supporting members, and forming an air chamber, and a fuel sifting receiving chamber below each set of grate bars, and means for delivering air under pressure to each 35 chamber.

9. An underfeed stoker, comprising at 40 least two horizontal retorts, extending from the front to the rear of the stoker, a dump grate located between the retorts and extending from the front to the rear of the stoker, grate bars between each retort and the dump grate and provided with air 45 passages, a separate support member for each retort, a separate support member for each set of grate bars, an air box mounted on each grate bar support member, and means 50 for delivering air to each air box and through the air boxes to passages formed within the grate bars.

10. An underfeed stoker, comprising two horizontal fuel feeding retorts, a dump 55 grate located between the retorts, a separate set of grate bars located between each retort and the dump grate, means for supporting each retort, means for supporting each set of grate bars independently of the 60 retorts including an air box located adjacent to the dump grate, and partition plates mounted on the grate bar supporting means for dividing the space below each retort and its corresponding grate bars into two air 65 chambers, one of said chambers extending

from each retort to the air box, and the other extending under one of said last mentioned chambers and one retort.

11. In an underfeed stoker, a fuel feeding retort, an ash discharge mechanism, grate 70 bars provided with twyer openings at the retort ends thereof and with passages in communication with said openings, said grate bars adapted to receive fuel from the retort, supporting means for said grate bars 75 and having air passages contiguous to the ash discharge mechanism and communicating with the grate bar passages, an air delivery chamber below the grate bars, a chamber located below the air delivery chamber 80 and communicating directly with the grate bar passages through the passages in said supporting means and from which air is delivered through said grate bar passages to the twyer openings and to said air delivery 85 chamber.

12. In an underfeed stoker, a retort, an ash discharge mechanism, grate bars located in parallel relation and extending from the retort to the ash discharge mechanism, an air 90 delivery passage formed in each grate bar, having its inlet at the ash discharge end of the bar and communicating with twyer openings formed in the retort end of the bar and an air delivery port located in the lower 95 face of the bar, a primary air chamber located below the grate bars and communicating directly with the inlets of the air passages formed in the grate bars through a passage independent of the ash discharge 100 mechanism, and a secondary chamber located immediately below the grate bars and between the bars and the primary air chamber and receiving air from the delivery ports 105 of the grate bars.

13. In an underfeed stoker, a retort, an ash discharge mechanism, grate bars located in parallel relation and extending from the retort to the ash discharge mechanism, communicating longitudinally extending air 110 passages formed in each bar, a primary air chamber in communication with the grate bar passages for delivering air thereto at the ash discharge end of the grate bar passages and also directly to separate twyers 115 located at the mouth of the retort, and a secondary air chamber located immediately below the grate bars and in communication with the passages thereof and above the primary air chamber for receiving the air delivered to the passages in the grate bars.

14. In an underfeed stoker, two side retorts, a centrally located ash discharge mechanism, two sets of grate bars each extending from one retort to the ash discharge mechanism and provided with an air passage, two primary air chambers each extending from the ash discharge mechanism under one set of grate bars and one retort and delivering air directly to twyers located at the mouth 130

of the retort and to the passages in the grate bars, and a secondary air chamber immediately below each set of grate bars and in communication with the passages thereof for receiving air delivered through the passages in the grate bars and for delivering the air so received between the grate bars to the fuel bed supported on the bars.

15. In an underfeed stoker, a retort, an ash discharge mechanism, grate bars located between the retort and the mechanism for receiving fuel issuing from the retort and discharging the fuel onto the mechanism, each grate bar being provided with an air passage and having an inlet at the ash discharge end of the bar, a chamber located below the grate bars and in communication with the passages thereof for receiving air which has traversed the air passages of the bars, a separate chamber located below the ash discharge mechanism, a primary air chamber communicating directly with the inlets of the grate bar passages, and means for delivering regulable amounts of air from the primary air chamber to the chamber below the ash discharge mechanism.
16. In combination in a stoker, a retort, a dump grate mechanism, grate bars between the retort and the mechanism, support members for the retort, grate bars and dump grate mechanism, comprising separately formed pedestals supporting the retort, sep-

arately formed grate bar support members secured to the pedestals, and on which said grate bars and said dump grate mechanism are mounted, and partition plates mounted on the members and dividing the space below the grate bars and retort into two chambers which communicate through passages formed in the grate bars.

17. In combination in a stoker, a retort, an ash discharge mechanism, grate bars extending from the retort toward the ash discharge mechanism, retort pedestals on which the side walls and the base plate of the retort are mounted, a separately formed grate bar supporting member secured to each pedestal, and partition plates mounted on said members and dividing the space below the grate bars into two chambers.

18. In combination in an underfeed stoker, a retort, an ash discharge mechanism, grate bars extending from the retort toward the ash discharge mechanism, separately formed U-shaped pedestals supporting and constituting a mounting frame for the retort sides and base plates, and separately formed grate bar supporting members secured to said pedestals and on which said grate bars are mounted.

In testimony whereof, I have hereunto subscribed my name this 18th day of September, 1916.

CHARLES F. MILLER.
